APPLICATOR COMB

Mario G. Usai, East Paterson, N. J.

Application August 26, 1954, Serial No. 452,360

10 Claims. (Cl. 132—110)

This invention relates to a device for applying creams, dyes, pomades and the like to the hair, and for cleaning the hair during the combing.

There are presently available devices of a comb-like nature for applying liquids and creams to the hair. Such devices have, in the main, however, been rather complicated, difficult to clean, and expensive to manufacture. Further, the available devices do not distribute the hair-treating material uniformly over the mass of hair on the head, nor do they insure the complete coverage of each hair by the material after only a few passages of the device through or over the hair, since they tend to coat only the outwardly presented surface of each hair.

The applicator device of my invention, which is particularly advantageous in the application of semi-solid material such as creams to the hair, is particularly characterized by its simplicity, the ease of its assembly and disassembly for cleaning purposes, the uniformity of distribution of the hair-treating material throughout the hair, and the thoroughness of coverage of each hair with the material after only a few strokes of the device through the hair. Further, the device provides for the ready substitution of different types of hair engaging members, such as rollers, whereby the device may quickly and easily be converted from an applicator to a hair cleaning device, and vice versa.

The invention has among its objects the provision of an improved applicator comb for treating hair, which uniformly distributes a controlled quantity of treating material throughout the hair.

A further object of the invention is the provision of an applicator comb of the indicated type having an applicator roll wherein the roll is so constructed as to insure the complete coverage of each hair by the treating material after a relatively few passes of the comb through the hair.

Other objects of the invention are to provide an applicator device which is simple and rugged in construction, which may readily be assembled and disassembled, and in which one hair engaging roll may easily be substituted for another so as readily to change the controlled rate of dispensing of the treating material or to change the device from an applicator to a hair cleaning device.

The above and further objects of the invention relating to economies of manufacture and use of the device will become more readily apparent in the following description of the illustrated, presently preferred embodiment thereof.

My invention is clearly defined in the appended claims. Where parts are, for clarity and convenience, referred to on the basis of their oriented position shown in the accompanying drawing, no limitation as to positioning of the entire structure is to be implied, since it will be understood that the entire structure may be inverted or that it may be used in any inclined position. Also in both the description and the claims, parts at times may be identified by specific names for clarity and convenience, but such nomenclature is to be understood as having the

2

broadest meaning consistent with the context and with the concept of my invention as distinguished from the pertinent prior art. The best form in which I have contemplated applying my invention is illustrated in the accompanying drawing forming part of this specification, in which:

Fig. 1 is a view in perspective of the applicator comb of the invention, a hair treating material-containing collapsible tube mounted thereon being indicated in dot and dash lines.

Fig. 2 is an exploded view of the applicator comb proper.

Fig. 3 is a view in vertical section through the applicator comb proper, the section being taken along a vertical central plane transverse to the length of the comb.

Fig. 4 is a view in horizontal section through the applicator comb, the section being taken along the line 4—4 in Fig. 3.

Fig. 5 is a view in perspective of an alternative, hair-cleaning, roll which may be substituted in the device of the invention for the applicator roll shown in Figs. 1-4, inclusive.

The applicator 10 shown is made up of two main parts, a comb-carrying bottom part 12 and an upper portion 14 having its bottom end telescoped into the upper end of part 12, as shown in Fig. 3. Parts 12 and 14 may advantageously be molded of plastic material although they may be made of other suitable materials such as metal. Such two parts, when fitted together, form a hollow box-like structure adapted to receive hair-treating material such as cream and to feed it to the applicator roll 16. The upper portion 14 is retained in assembled position (Figs. 1 and 3) on the lower portion 12 by rounded projections 18 and 20, on the inner surfaces of the end and side walls, respectively, of portion 12 which snap into the rounded depressions 22 and 24, respectively, on the end and side walls of portion 14 when the latter is fully telescoped into part 12.

Projecting horizontally outwardly from the bottom edge 40 of the forward side wall 26 of part 12 is a comb 28, the bottom of which is substantially flush with the bottom edge of such side wall. Such bottom edge is provided with shallow grooves 30 which extend in the same direction as the grooves 32 between the teeth of the comb. In the comb shown, grooves 30 are aligned with alternate grooves 32, an arrangement which appears to encourage the random separation of the strands of hair as they leave grooves 32 and approach the applicator roll 16. It will be understood, however, that, if desired, grooves 30 may be the same in number as grooves 32 and be aligned with them.

The horizontal applicator roll 16, located within the closure formed by parts 12 and 14, is mounted, in the fully assembled device, so that a shallow segment at the bottom thereof protrudes through the opening 48 at the bottom of part 12, and lies below the bottom part 12, whereby the strands of hair leaving the grooves 30, when the device is passed over the head in the direction of the arrow in Fig. 3 and the roll 16 is pressed firmly down against the hair, are in intimate contact with the peripheral surface of the roll. The roll 16, in the illustrated device, is journaled on the depending portions 34 of the end walls of portion 14. A pintle pin 36, which extends axially through and is freely slid able in roll 16, has its end portions positioned in holes 38 in portions 34 and its end surfaces substantially flush with the outer side surfaces of parts 34 when the pin is centered in the roll.

The pin is locked in such roll retaining position, when part 14 is telescoped into part 12, by the substantial abutment of the end surfaces of the pin against the inner surfaces of the end walls of part 12. When it is desired to disassemble the roll 16 from the device,

as to clean the device or the roll, or to substitute a different roll therefor, it is merely necessary to withdraw part 14 from part 12 of the device, and to push the pin 36 out of the hole 38 in one of parts 34, thereto to free the roll at such end to allow its being tipped downwardly relative to part 14 and then withdrawn axially from the other of parts 34. The pin 36 carried by the same or a replacement roll may be assembled in part 14 by the reverse of the above operations, or it may be snapped upwardly into holes 38 through slots 39 in parts 34.

The applicator device is supplied with hair treating material, such as cream, from a reservoir such as a collapsible tube 40 mounted in inverted position on top of part 14. As shown, part 14 is provided with a heavy top wall 42 having a threaded opening 44 therein, the neck 46 of the collapsible tube being threadedly received in opening 44. The space within the device 10 above the roll 16 is filled with semi-solid, hair-treating material by squeezing the tube 40 to subject the material therein and in the cavity in the applicator comb body to pressure to cause the material to flow downwardly into such cavity and onto the roll 16. The material has sufficient viscosity so that it does not flow appreciably, if at all, under the effect of gravity alone. Thus the hair-treating material will not leak or drip from the device during normal storage of the applicator in either a vertical or a horizontal position.

To insure the dispensing of the treating material in the desired amount and at the desired locations from the applicator, there is provided means to meter the flow of the material onto the roll 16. Roll 16 is made of such length that its ends lie close to the ends of the opening 48 through which a portion of the roll protrudes at the bottom of the part 12 of the applicator. Thus, even when the hair treating material in the device above the roll is subjected to appreciable pressure, as by the squeezing of tube 40, an insignificant amount of hair-treating material will escape along the ends of the roll when it is either at rest or being rotated during use.

The rate at which such material is fed to roll 16, and consequently the thickness of the film of material present on the roll during its rotation while being traversed over the hair, are limited and controlled by the doctor blade-like lower side members 50 and 52 on part 14 of the device. These members, which are integral with the remainder of part 14, may be tapered in thickness in a downward direction, so that the lower edges thereof are quite thin and flexible. The members 50 and 52 are flexed inwardly by the downwardly and inwardly curved thickened lower edges 54 and 56, respectively, on the side walls 26 and 58 of the lower part 12 of the applicator. When parts 12 and 14 are assembled in operative position, as shown in Fig. 3, the lower edges of the members 50 and 52 are thus brought close to the periphery of roll 16. In some instances the edges of members 50 and 52 may lightly contact the periphery of the roll, to provide a very thin coating of material thereon, and thus a slow rate of feed of material thereto. This condition may be desirable with some hair-treating materials, particularly when the roll 16 shown in detail in Fig. 3 and to be described hereinafter, is employed. For other hair-treating materials, and with other types of applicator roll, it may be desired to have the lower edges of the members 50 and 52 slightly spaced from the periphery of the roll. This can be accomplished by making such other applicator roll, which is to be substituted for roll 16, of slightly smaller diameter than roll 16.

The roll 16 is provided (Fig. 4) with a first shallow helical groove 60 inclined in one direction and with a second similar shallow helical groove 62 inclined in the opposite direction so that it periodically crosses the first groove, as shown. Such grooves will be substantially full of hair-treating material, such as cream, when they

are exposed to contact with the hair at the bottom of the part 12, even though doctor blade members 50 and 52 contact the periphery of roll 16. Thus a uniform quantity of material will be on the exposed area of the roll, assuming the material in the applicator cavity is subjected to enough pressure to cause the material to feed downwardly to the roll.

The grooves have the further important function of distributing the hair-treating material substantially uniformly over the entire surface of each hair strand with but a few passes of the comb of the device through the hair. As the comb 28 of the device is passed through the hair, with the device held so that the bottom of roll 16 lies on top of the hair on the head, the strands of hair in each groove 32 of the comb are led to the roll along grooves 30. Some of the thus gathered hair strands will enter groove 60, and will tend to follow such groove and be turned by it in a first direction about the longitudinal axis of the hair strand as the device 10 is traversed over the head. Others of the hair strands will enter groove 62, and will tend to follow such latter groove and be turned by it in a second, reverse direction about its longitudinal axis. One pass of the device 10 along one zone of the hair will suffice substantially to coat all the surface of each hair in such zone, and a few repeated passes along the same zone, in which at least some of the hair strands will be differently gathered and will enter a different one of grooves 60 and 62 each time, will suffice to coat the entire surface of each hair strand from its root to its tip.

For some coating operations it may be desired to use a plain, ungrooved circular cylindrical applicator roll, although this in general requires a larger number of passes of the device over the hair to insure the substantially complete coating of each hair.

The device of the invention is also useful for cleaning the hair, as in preparation for its being coated with hair-treating material. For such hair cleaning process, it is preferred that the tube 40 be removed, the cavity in device 10 be cleaned out, and applicator roll 16 be removed and replaced by the cleaning roll 16' (Fig. 5). This roll may be made of felted fibers, and be fairly soft and open structured with short fibers projecting therefrom, although self-sustaining. It is preferred that roll 16' be made of such diameter that the outer ends of its peripherally exposed fibers just clear the lower edges of members 50 and 52. As the device with roll 16' installed therein is run over the hair, the soft, open structured roll 16' is pressed against the hair and tends to remove dust, dirt, and dandruff therefrom. After such use of the device, the roll 16' may be removed and brushed or washed to relieve it of the foreign material it has removed from the hair.

I claim:

1. A device for applying a material to hair, comprising a body having a material receiving cavity therein, an applicator roll journaled on the body so that the peripheral surface of the roll is alternately exposed at the bottom of the body and positioned within the cavity as the roll rotates, and a comb protruding from a bottom edge of the body for aligning strands of hair and leading them to the periphery of the roll as the comb is traversed through the hair.

2. A device for applying a material to hair, comprising a body having a material receiving cavity therein, an applicator roll journaled on the body so that the peripheral surface of the roll is alternately exposed at the bottom of the body and positioned within the cavity as the roll rotates, a comb protruding from a bottom edge of the body for aligning strands of hair and leading them to the periphery of the roll as the comb is traversed through the hair, and a doctor blade substantially engaging the periphery of the roll adjacent the location at which points on such periphery leave the cavity during normal rotation of the roll.

3. A device for applying a semi-solid material to hair, comprising a body having a material receiving cavity therein, an opening in the bottom of the body, an applicator roll journaled in the body near the bottom of the body so that points on the peripheral surface of the roll alternately extend beyond the bottom of the body through said opening and are positioned within the cavity as the roll rotates, the roll interfitting fairly snugly with the opening, means for subjecting the material in the cavity to pressure to cause it to be deposited on the periphery of the roll internally of the cavity, and a comb protruding from the forward bottom edge of the body for aligning strands of hair and leading them to the periphery of the roll as the comb is traversed through the hair.

4. A device for applying a semi-solid material to hair, comprising a body having a material receiving cavity therein, the body being formed of an upper and a lower part telescoped together, an opening in the bottom of the lower part, an applicator roll journaled in the body near the bottom thereof so that points on the peripheral surface of the roll alternately extend beyond the bottom of the body through said opening and are positioned within the cavity as the roll rotates, the roll interfitting fairly snugly with the opening, and means for mounting the neck of a collapsible tube of material on the body whereby the cavity may be filled with material and such material subjected to pressure.

5. In the device set out in claim 4, the lower end of the upper part of the body lying within the lower part of the body, means selectively locking the two parts of the body in fully telescoped assembled position relative to each other, and means journaling the roll between the opposite lower ends of the upper part of the body.

6. In the device set out in claim 5, the means journaling the roll comprising a pintle pin freely slideable through the roll and having its opposite ends received in holes in the opposite end walls of the upper part of the body, the opposite end surfaces of the pin at least substantially abutting the inner surfaces of the opposite end walls of the lower part of the body.

7. A device for applying a cream-like material to hair, comprising a body having a material receiving cavity therein, the body being formed of an upper and a lower part, both formed of molded plastic material and telescoped together with the lower end of the upper part lying within the lower part, an opening in the bottom of the lower part, an applicator roll journaled in the body near the bottom thereof so that points on the peripheral surface of the roll alternately extend beyond the bottom of the body through said opening and are positioned within the cavity as the roll rotates, the roll interfitting fairly snugly with the opening, the roll having shallow

crossing helical grooves of opposite hand on its periphery, doctor blades on the lower forward and rear side edges of the upper part, means on the lower part adjacent the side edges of the opening in the bottom of the body urging the blades inwardly toward the periphery of the roll whereby substantially to engage it, means to subject material in the cavity to pressure, and a comb integral with the lower part of the body and protruding from the bottom edge thereof for aligning strands of hair and leading them to the periphery of the roll as the comb is traversed through the hair.

8. A hair treating device comprising a body, a roll journaled on the body so that the peripheral surface of the roll is alternately exposed at the bottom of the body and positioned within the body as the roll rotates, and a comb protruding from a bottom edge of the body for aligning strands of hair and leading them to the periphery of the roll as the comb is traversed through the hair.

9. A device for applying a material to hair, comprising a body having a material receiving cavity therein, an applicator roll journaled on the body so that the peripheral surface of the roll is alternately exposed at the bottom of the body and positioned within the cavity as the roll rotates, the roll having crossing helical grooves of opposite hand on its periphery, and a comb protruding from a bottom edge of the body for aligning strands and leading them to the periphery of the roll as the comb is traversed through the hair.

10. A device for applying a semi-solid material to hair, comprising a body having a material receiving cavity therein, an opening in the bottom of the body, an applicator roll journaled in the body near the bottom of the body so that points on the peripheral surface of the roll alternately extend beyond the bottom of the body through said opening and are positioned within the cavity as the roll rotates, the roll interfitting fairly snugly with the opening, doctor blades positioned in the cavity and urged inwardly toward the periphery of the roll and substantially engaging it, means for subjecting the material in the cavity to pressure to cause it to be deposited on the periphery of the roll internally of the cavity, and a comb protruding from the forward bottom edge of the body for aligning strands of hair and leading them to the periphery of the roll as the comb is traversed through the hair.
